US0D1098094S

(12) **United States Design Patent** (10) Patent No.: **US D1,098,094 S**
(45) Date of Patent: ** Oct. 14, 2025

(54) **MOBILE ELECTRONIC DEVICE GRIP WITH ROUND BASE**

(71) Applicant: **PopSockets LLC**, Boulder, CO (US)

(72) Inventors: **Randy Yang Chiang**, Boulder, CO (US); **Lawrence Herman Fong**, Boulder, CO (US); **Michael Kory**, Boulder, CO (US); **David Czarnecki**, Boulder, CO (US); **Nicholas Von Borgen**, Boulder, CO (US); **Yinju Chen**, Boulder, CO (US); **Altan Nahum**, Boulder, CO (US)

(73) Assignee: **POPSOCKETS LLC**, Boulder, CO (US)

(**) Term: **15 Years**

(21) Appl. No.: **29/878,557**

(22) Filed: **Jun. 23, 2023**

Related U.S. Application Data

(63) Continuation-in-part of application No. 17/500,789, filed on Oct. 13, 2021.

CLAIM

The ornamental design for a mobile electronic device grip with round base as shown and described.

DESCRIPTION

FIG. 1 is a perspective view of a fully expanded mobile electronic device grip with round base according to the present invention;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

(Continued)

The broken lines are included for the purpose of illustrating portions of the article that form no part of the claimed design.

1 Claim, 7 Drawing Sheets
